LAST EXPANDING MACHINE

Jacob S. Kamborian, West Newton, Mass.

Application November 29, 1946, Serial No. 713,183

9 Claims. (Cl. 12—15)

1

This invention pertains to shoe-lasting apparatus and more especially to a last expanding machine for use in applying stress to the assembled upper and sock lining unit of a force-lasted shoe by relative movement of the forepart and heel portions of a longitudinally expandible last.

In the manufacture of force-lasted, California, or platform type shoes, the margin of the upper is permanently secured to the edge portion of the sock lining or insole before introduction of the last, and the shaping of the upper is accomplished by forcing the last into the assembled upper and sock lining. The introduction of the conventional hinged last into such an assembly is difficult and often results in bursting the upper at its rear seam. For this reason it is quite common to use an undersized last but this necessarily means that the upper is never subjected to proper lasting stress and is not accurately shaped. To avoid this difficulty, as described in my U. S. Patent No. 2,427,354 granted September 16, 1947, a longitudinally expandible last may be employed, comprising independent forepart and heel portions which may be disposed in juxtaposed relation (preparatory to the introduction of the last into the assembled upper and sock lining) and then separated (after the last has been slipped into the upper) so as to increase the effective length of the last. In this way the last may be introduced while it is of minimum length and then, in expanding it to its full predetermined length, the upper is properly stressed and shaped. Preferably releasable locking or retaining means is provided in order to hold the last expanded as long as may be desired.

The forepart and heel portions of such an expandible last, after it has been introduced into the assembled sock lining and upper, may be moved apart, for example by introducing a suitable tool before them, and applying force to pry them apart, but this is a clumsy and laborious method and injurious to the last. Moreover, it is as essential that the last be not unduly elongated as it is that the last be sufficiently elongated to insure proper stressing of the upper. To facilitate the separation of the last parts it has been proposed to provide each of the last parts with a socket or spindle-receiving hole designed to receive separable spindles or other appliances by means of which the last members may be forced apart.

The object of the present invention is to provide improved apparatus, including such separable spindles together with means whereby said

2

spindles may be relatively separated to a predetermined extent and in an expeditious and ready way. A further object is to provide a simple last-expanding apparatus operable, for example, by the worker's foot and having provision for adjusting the effective spacing of the socket-engaging elements whereby the machine may be adapted for use with lasts of different sizes or in the lasting of materials of different types. A further object of the invention is to provide last-expanding apparatus so designed as to permit the ready removal of the last from the expanding mechanism after the last has been expanded and while it is held in its fully expanded condition. Other and further objects and advantages of the invention will be pointed out in the following more detailed description and by reference to the accompanying drawings wherein

20 Fig. 1 is a plan view of the improved apparatus;

Fig. 2 is a vertical section substantially on the line 2—2 of Fig. 1 with certain parts broken away;

25 Fig. 3 is a fragmentary transverse vertical section on the line 3—3 of Fig. 2;

Fig. 4 is a transverse vertical section on the line 4—4 of Fig. 2;

Fig. 5 is a transverse vertical section on the line 5—5 of Fig. 2;

Fig. 6 is a side elevation, partly in vertical section, showing an expandible last while in its contracted position, portions of the spindles of the expanding machine being shown;

30 Fig. 7 is a view similar to Fig. 6 but showing the last fully expanded; and

Fig. 8 is a fragmentary view, similar to Fig. 6, but showing the parts positioned to permit removal of the expanded last from the spindles.

40 Referring to the drawings, the numeral 1 designates the machine base or frame. As here illustrated this base or frame is a hollow casting having the bottom flange 2 designed to receive bolts for securing the base or frame to a suitable bench or suitable support. The base

comprises the spaced side walls S (Fig. 5), and the top wall T. A carriage guide 4 is mounted on the top wall T and secured in place by bolts

45 5. This carriage guide is provided with a longitudinal, rectilinear guideway 6 in its under surface in which a carriage 7 (Fig. 2) is arranged to slide from front to rear. A coiled extension spring 8 is secured at its forward end to a pin 9 fixed to the carriage, the rear end 50 of the spring being connected to an adjusting

screw 10 having threaded engagement with a bore in the rear end of the guide 4. A suitable screw 11, also having threaded engagement with a bore in the rear end of the guide 4, is arranged to engage an abutment surface 12 (Fig. 1) at the rear end of the carriage, thereby to limit movement of the carriage to the rear, or to the right, as in Figs. 1 and 2.

The top wall of the guide 4 is provided with an elongate slot 13 (Fig. 2) at its forward portion, this slot extending to the forward end of the guide. Within the forward end of this slot there is arranged a spindle base 14 having a screw threaded stud 15 which engages a threaded bore in the forward end of the carriage 7. The spindle base carries the spindle 16 designed to enter the rear socket of the expansible last. The axis of this spindle 16 is vertical, as here illustrated, and always remains vertical regardless of the position of the carriage.

A block 17 (Fig. 3) is secured to the under side of the front end of the carriage by bolts 18 and this block is provided with a horizontal threaded bore which receives an adjustable stop screw 19 (Fig. 2).

Near the forward part of the base or frame 1 and near the bottom of the latter there is arranged a transverse rod 20 (Fig. 2) which may be fixed at its opposite ends in bosses 21 of the base. On this rod 20 there is pivotally mounted a spindle support 22 which extends up through an elongate slot in the forward part of the top wall T of the base and which also extends up through an elongate slot 23^a in the forward part of the carriage 7. The upper end of this pivotal support 22 is substantially flush with the upper surface of the carriage when the support 22 is vertical. The upper end of the support 22 is provided with a screw threaded bore which receives a threaded stud 24 (Fig. 2) projecting downwardly from a spindle base 24^a from which projects the spindle 25 which is designed to engage the forward spindle socket of the last. The spindles 16 and 25 are preferably of the same height when the parts occupy the normal or initial position shown in Fig. 2, with their axes parallel and vertical. Preferably these spindles have smoothly curved upper surfaces to facilitate their entry into the last sockets.

A transverse shaft 26 is mounted to turn in bearings in the opposite side walls S of the base and the forward end of a lever 27 is clamped to the mid-portion of this shaft 26. Spacing sleeves K (Fig. 5) may be provided to keep the lever 27 centrally located and in the vertical plane of the pivoted support 22. The upper end of a connecting rod 28 (Fig. 2) is pivotally secured to the right-hand upper end of the lever 27 and the lower end of this connecting rod 28 is connected to a foot-actuated treadle (not shown) by means of which the rear end of the lever 27 may be swung downwardly. A coiled tension spring 29, or equivalent means, tends to hold the rear end of the lever 27 in its uppermost position.

A link 30 (preferably bifurcated to embrace the pivoted support 22) is connected at its forward end to the support 22 by a pivot member 31 and is connected at its rear end to the lever 27 by a pin 32. If desired the lever 27 may be connected to the shaft 26 in such a way as to provide for varying the effective length of the lever, for example, it may be mounted on the shaft 26 with an interposed eccentric 260 which may be turned to different angular positions before the lever is clamped in place. As illustrated the effective

length of the lever arm between the shaft 26 and the pin 32 is less than the effective length of the lever arm between the shaft 26 and the pivotal connection of the rod 28, so that the link 30 and lever 27 provide a mechanical advantage such that the pressure on the treadle is multiplied in transmitting it to the swinging spindle support 22.

The apparatus described is designed for use with a last of the general type illustrated in Figs. 6, 7 and 8. This last comprises the heel portion 33 and the forepart portion 34. A pair of rigid guide rods 35 and 36 is secured in the heel part 33, the guide rods being slidable in parallel bores in the forepart portion 34. The rod 36 is provided with a notch in its upper surface and a spring-pressed latch 40, carried by the forepart portion 34, is designed to enter the notch in rod 36 when the last is fully expanded and thus lock the last parts at a fixed distance apart. The last parts 33 and 34 are provided with the parallel spindle sockets 41 and 42, respectively.

When the apparatus above described is in the normal, initial, or last-receiving position the parts are as shown in Figs. 2 and 6 with the carriage 7 in its rearward position engaging the stop 11 and with the spindle support 22 in its forward position engaging the stop 19. In this position, the spindles 16 and 25 are vertical and parallel and spaced apart so that they may readily be slipped into the sockets 41 and 42 of the fully contracted last, as illustrated in Fig. 6.

Although the shoe upper is not herein illustrated, it will be understood that the assembled upper unit, comprising the united upper and sock lining or their equivalents, will have been drawn over the contracted last before the latter is expanded by the operation of the present apparatus.

Having mounted the last on the spindles, the operator places his foot on the treadle, pulling down on the rod 28 and thus swinging the spindle support 22 rearwardly (Fig. 7). The spindle 25 is sufficiently loose in the socket 42 so that such rearward swing of the spindle support is possible without clamping the spindle 25 in its socket. Since the maximum expansion of the last need not exceed one-half inch, or thereabouts, this action is readily possible. When the last has thus been expanded to the maximum predetermined extent, thereby subjecting the upper to the requisite lasting stress, the latch or holding member 40 snaps into the notch and thus locks the last in its fully extended position. Assuming that the shoe upper has been drawn over the last while the latter was in the fully contracted position, as shown in Fig. 6, this expansion of the last places the upper under substantial longitudinal stress sufficient to conform the upper to the last. The stressed upper exerts tension tending to contract the last, but contraction is prevented by the latch 40. The operator now removes his foot from the treadle and the spring 29 tends to raise the lever 27 and thus to swing the spindle support 22 forwardly. In the fully expanded position the axes of the spindles 16 and 25 are in upwardly divergent relationship, as shown in Fig. 7. It would be very difficult to pull the last from off the spindles in this position of the parts, but when the operator's foot is removed from the treadle the spindle 25 moves back toward the initial or normal position, as shown in Fig. 2. Since the spindle sockets 41 and 42 are now at a fixed distance apart, the spindle 16 is moved forwardly from its normal position, the carriage moving in a rectilinear path so that the spindle 16 remains vertical.

When the spindle 25 has resumed the vertical position, the two spindles are again parallel (Fig. 8) and the last may readily be withdrawn by direct outward lift from the spindles. As soon as the last is thus withdrawn, the spring 8 moves the carriage back to its initial position and the apparatus is ready to receive another last.

While as here illustrated the spindle 25 is carried by a pivotal support, it is contemplated that the support for the spindle 25 may, if desired, be mounted to move in a rectilinear path toward and from the spindle 16, although the pivoted support is desirable by reason of its simplicity. Likewise, although the spindle support 25, as here described, is designed for actuation by a treadle, it is obvious that a hand operated lever might be used for swinging it or that the support 25 might be mechanically actuated through a suitable motor and clutch device, for example.

Moreover, the kind of locking or retaining means employed to hold the last expanded is immaterial to the present invention.

While one desirable embodiment of the invention is herein illustrated by way of example, it is to be understood that the invention is capable of embodiment in other specific constructions as defined by the appended claims.

I claim:

1. Apparatus for use in expanding a longitudinally expansible shoe last comprising independent forepart and heel portions each provided with a spindle socket, said apparatus comprising a pair of separable, normally parallel spindles, a sliding carriage on which one of the spindles is mounted, a pivotal support for the other spindle, means normally holding the spindles in parallel relation, a spring urging the carriage in a direction to move its spindle toward the pivotally supported spindle but permitting the carriage to move in the opposite direction from its normal position, stop means for limiting movement of the carriage by the spring, and means for swinging the pivotally supported spindle thereby to expand a last mounted on the spindles.

2. Apparatus for use in expanding a longitudinally expansible shoe last comprising independent forepart and heel portions each provided with a spindle socket, means operative to lock the forepart and heel portions at a fixed distance apart when the last is fully expanded, said apparatus comprising a pair of separable, normally parallel spindles, means supporting one spindle to swing about a pivotal axis, means operative to swing the latter spindle thereby to separate the heel and forepart portions of a last mounted on the spindles until they are locked in the fully expanded position, and means so supporting the other spindle that as the pivoted spindle is thereafter returned to its normal position, the distance between the spindles may remain at the maximum, resultant from the last-expanded movement of the pivotal spindle.

3. Apparatus for use in expanding a longitudinally expansible shoe last comprising independent forepart and heel portions each provided with a spindle socket, automatic means operative to lock said forepart and heel portions at a fixed distance apart when the last is fully expanded, said apparatus comprising a pair of separable, normally parallel spindles, means pivotally supporting one spindle to swing about a transverse axis, means to swing said pivoted spindle so as to incline its axis relatively to that of the other spindle, and to separate the forepart and heel portions of a last mounted on the spindles until they

are locked in the fully expanded position, and means supporting the other spindle to move while its axis always remains parallel to its normal position, as the pivoted spindle is restored to its normal position, so that the distance between the spindle axes, when the pivoted spindle regains its normal position is substantially the same as when the pivoted spindle is at its maximum angle of inclination.

4. Apparatus for use in expanding a shoe last comprising separable forepart and heel portions each having a spindle socket and automatic means for locking said last portions at a fixed distance apart when the last is fully expanded, said apparatus comprising a spindle whose axis is always substantially vertical and a spindle which is pivotally supported so that its axis may be inclined to the vertical, means normally holding said spindles parallel and at such a distance apart that they may be entered into the corresponding spindle sockets of the contracted last, means for swinging the pivoted spindle to separate the last parts until they are locked with the last fully expanded, and means for supporting the vertical spindle so that it may remain at the same effective distance from the pivoted spindle while the latter is being restored to normal position and while the expanded last remains upon the spindles thereby to facilitate removal of the last from the spindles.

5. Apparatus for use in expanding a shoe last comprising separable forepart and heel portions each having a spindle socket and automatic means for locking said last portions at a fixed distance apart when the last is fully expanded, said apparatus comprising a spindle whose axis is always substantially vertical and a spindle which is pivotally supported so that its axis may be inclined to the vertical, means normally holding said spindles parallel and at such a distance apart that they may be entered into the corresponding spindle sockets of the fully contracted last, means for swinging the pivoted spindle to separate the last parts until they are locked with the last fully expanded, a horizontally slideable carriage on which the first spindle is mounted, a spring urging the carriage in a direction to move the first spindle toward the pivoted spindle, and a stop element for limiting such movement of the carriage, the carriage being movable in the opposite direction whereby the spindle mounted on the carriage may remain at the same effective distance from the pivoted spindle as the latter is restored to normal position while the expanded last remains upon the spindles thereby to facilitate removal of the last from the spindles.

6. Apparatus for use in expanding a shoe last comprising separable forepart and heel portions each having a spindle socket and automatic means for locking said last portions at a fixed distance apart when the last is fully expanded, said apparatus comprising a spindle whose axis is always substantially vertical and a spindle which is pivotally supported so that its axis may be inclined to the vertical, means normally holding said spindles parallel and at such a distance apart that they may be entered into the corresponding spindle sockets of the fully contracted last, means for swinging the pivoted spindle to separate the last parts until they are locked with the last fully expanded, a horizontally slideable carriage on whose forward portion the first spindle is fixed, the carriage having a longitudinal slot in which the pivoted spindle may freely move, a spring urging the carriage rearwardly, an ad-

justable stop limiting such rearward movement of the carriage and determining the normal position of the first spindle, the carriage being movable forwardly from its normal position in opposition to said spring whereby while the last remains locked in expanded position, the pivoted spindle may be restored to normal position before removal of the last from the spindles.

7. Apparatus for use in expanding a shoe last comprising separable forepart and heel portions each having a spindle socket and means for locking said last parts at a fixed distance apart when the last is fully expanded, said apparatus comprising a hollow base having a guideway for a horizontally slidable carriage, a spring urging the carriage rearwardly, an adjustable stop limiting rearward movement of the carriage and determining its normal position, the carriage being movable forwardly from its normal position in opposition to said spring, a spindle fixed to the forward part of the carriage, the carriage having an elongate slot, a second spindle supported to swing about a pivotal axis transverse to the path of travel of the carriage and located within the base and below the carriage, the pivoted spindle projecting up through the slot in the carriage, means normally holding the pivoted spindle with its axis parallel to that of the carriage supported spindle and means, including mechanism housed within the base, for swinging the pivoted spindle so as to move its upper end rearwardly and away from the carriage-supported spindle, thereby to separate the forepart and heel portions of a last mounted on the spindles until the last is fully expanded and locked.

8. Apparatus for use in expanding a shoe last comprising separable forepart and heel portions each having a spindle socket and means for locking said last portions at a fixed distance apart when the last is fully expanded, said apparatus comprising a hollow base having a guideway having a horizontally slidable carriage, a spring urging the carriage rearwardly, a stop limiting rearward movement of the carriage and determining its normal position, the carriage being movable forwardly from normal position in opposition to the spring, a spindle fixed to the carriage, a sec-

ond spindle rearward of the carriage-supported spindle, supported to move rearwardly relatively to the carriage, means urging the second spindle in a forward direction, means limiting forward movement of the second spindle whereby when the spindles are in normal position they are substantially parallel and spaced to permit their entry into the corresponding sockets of the last members, and means operative to move the second spindle rearwardly relatively to the carriage-supported spindle thereby to separate the forepart and heel portions of the last mounted on the spindles until the last is fully expanded.

9. Apparatus for use in expanding a longitudinally expansible shoe last comprising independent forepart and heel portions each provided with a spindle socket, said apparatus comprising a pair of separable, normally parallel spindles, a sliding carriage on which one of the spindles is mounted, a pivotal support for the other spindle, means normally holding the spindles in parallel relation, a spring urging the carriage in a direction to move its spindle toward the pivotally supported spindle but permitting the carriage to move in the opposite direction from its normal position, stop means for limiting movement of the carriage by the spring, means including a lever and a treadle rod for swinging the pivotally supported spindle thereby to expand the last mounted on the spindle and means to change the effective length of said lever to modify the mechanical advantage transmitted from the treadle through the lever to the pivotally supported spindle.
